[57] **CLAIM**

The ornamental design for white board copier, as
shown and described.

DESCRIPTION

FIG. 1 is a front and left perspective view of a white
board copier showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof; and

FIG. 8 is another embodiment of my new design of
FIGS. 1-7 wherein the board is shown laterally.
